UNITED STATES PATENT OFFICE.

CHARLES B. BUERGER, OF PITTSBURGH, PENNSYLVANIA, ASSIGNOR TO GULF OIL BURNER COMPANY, OF PITTSBURGH, PENNSYLVANIA, A CORPORATION OF PENNSYLVANIA.

LIQUID-FUEL BURNER.

Application filed August 17, 1926. Serial No. 129,826.

This invention relates to liquid fuel burners; and it comprises a burner having a lower compartment defined by a base and an overlying member; means for directing an up-draft of air through said base laterally to the periphery of the burner and discharging it with a swirling motion; a fuel oil distributor extending above the upper surface of said member; means for directing a portion of the current of air flowing through the base upwardly through said member and laterally beneath the distributor; a plate of generally conical shape overlying and resting upon said member, the body portion of the plate being spaced from the member; a cap overlying and resting upon said distributor to permit the flow of fuel therefrom but shield it from the heat of the flame when the burner is in use; means projecting downwardly from the base for adjustably positioning the burner in a furnace; a fuel overflow pipe communicating with the base of the burner, adapted to carry off excess fuel as it is delivered from a source of supply, and a removable guard positioned to enclose said overflow opening in the base of the burner; all as will herein-after be more fully described and claimed.

The present burner is adapted particularly for household use in existing coal burning furnaces employing grates, and it comprises a base with means for accurately installing it in a level position upon the grate bars of a furnace. The base is open at both top and bottom and a cover member of generally conical shape is mounted upon the base but is spaced from it by a plurality of curved vanes which are preferably formed integrally with the cover member and extend downwardly into contact with the flared upper end of the base. A plate overlies the cover member with its body portion spaced therefrom to provide an air space for preventing overheating of the cover by the flame of the burner. Both the plate and cover have central openings which are aligned when the burner is assembled and through which an oil feed pipe extends. The upper end of the feed pipe terminates in a distributor for liquid fuel which is radially grooved on its upper face and vertically grooved around its periphery to evenly distribute the liquid fuel over the conical surface of the overlying plate. A cap rests upon the distributor to protect it from the direct heat of the flame which might cause preignition of the fuel or its carbonization prior to its delivery to the intended point of combustion. The cap is formed with an internal annular shoulder resting upon the peripheral edge of the distributor so that a space is formed above the upper face of the distributor and an annular space is provided around its sides. It is essential that the burner be mounted in a level position so that the oil or other fuel may be evenly distributed over the face of the overlying plate and produce a symmetrical flame, combustion taking place entirely around the burner. For this purpose adjustable legs are provided depending from the burner base and adapted to rest upon or between the grate bars of a furnace, or upon any surface on which the burner is mounted. The base of the burner is formed with an annular trough in which the liquid fuel is received in the event that the flame is accidentally extinguished but the flow of fuel continued. An overflow pipe communicates with this trough and is intended to convey the fuel accumulated in the trough to an automatic flow control device such as is described in my co-pending application, Serial No. 122,187, filed July 13, 1926, whereby when a predetermined amount of overflow liquid has accumulated further delivery of fuel to the burner is stopped. In the present invention a removable guard is provided for the overflow pipe.

It is an object of my invention to provide a liquid fuel burner of simple and inexpensive construction, which is easily assembled and in which the parts are protected to insure efficient operation.

Another object is to provide a burner which produces a substantially solid conical flame, the outer surface of which is of spiral form.

A further object is to provide a burner which may be adjustably supported within a furnace in level position irrespective of the nature of the surface upon which it is mounted.

Other and further objects will be apparent

from the following description and drawings, in which:

Figure 1 is a top plan view of the burner comprising the present invention, partly in section.

Figure 2 is a fragmentary detail view of a portion of the base of the burner showing the construction of the adjustable legs for supporting the burner in level position.

10 Figure 3 is a vertical sectional view of the burner taken along line 3-3 of Figure 1.

Figure 4 is a detail sectional view of the liquid overflow guard taken along line 4-4 of Figure 1.

15 Referring more particularly to the drawings:-

The burner base comprises an upwardly extending collar portion 1 flared outwardly at its bottom and terminating in an upwardly 20 extending annular wall 2, while its upper portion terminates in an outturned flange 3.

25 A cover 4 is preferably formed with downwardly projecting curved vanes 5 which rest upon the flange 3 of the base and extend to some extent within the collar portion thereof, thus spacing the cover above the base and defining a series of curved passages between the base and cover. A burner plate 6 rests upon the cover 4, such plate being annularly recessed as at 7 to provide an air space which 30 serves to prevent overheating of the cover and distributor. The distributor 8 comprises a circular member axially bored to receive the end of fuel feed pipe 9 and having its upper 35 face grooved radially for the delivery of oil evenly therearound, the vertical side face of the distributor likewise being grooved for conducting the oil to the surface of the burner plate 6. The grooves in the upper and side 40 faces of the distributor offer a resistance to the flow of oil and since all of the grooves are identical in formation the flow of fuel is equalized. Legs 10 depend from the under side of the distributor and engage the edge of 45 the opening 11 which is formed in the cover and burner plate to position the distributor so that it lies centrally of the opening and slightly above the plate 6.

50 A cap 12 overlies the distributor head, such cap being formed with an annular internal shoulder 13, annularly grooved as at 14 to rest upon the periphery of the distributor head. A space 15 is thus defined above the upper 55 face of the distributor as well as an annular space about its side. One or more openings 16 are preferably provided in the cap 12 for venting the space 15.

Depending from the base of the burner are a plurality of screw-threaded legs 17 each 60 provided at its lower end with an adjustable foot 18. Each foot 18 comprises an internally screw-threaded metal member, tapered at its lower end and formed with radially projecting lugs 19 and 20 extending from its side. 65 These lugs serve as a means for turning the

foot 18 for adjusting it on the screw-threaded leg 17 or if, when in use, the foot will normally extend between adjacent grate bars such lugs will engage the grate bars to support the burner properly.

70

Adjacent the overflow opening in the base of the burner integral upstanding walls 21, 22 and 23 are formed. A metal guard 24, retained by screw 25, overlies the walls 22 and 23 and is supported along its longitudinal edge 75 upon wall 21. The guard is provided with slits 26 adjacent the bottom of its downturned ends and lying below or on a plane with the upper surfaces of walls 22 and 23 whereby, when the burner is in operation and overflow 80 fuel accumulates in the trough of the base a liquid seal will be provided to prevent the spread of fire in the event that that oil which is contained in the trough becomes ignited.

85

In the operation of the burner, air passing upwardly through the base of the burner is divided into two streams one of which passes laterally between the base and cover to the periphery of the burner where it is given a swirling motion by reason of the curved 90 vanes, the other stream passing upwardly through the cover member and burner plate where it is discharged laterally from under the distributor head. Oil flowing from the end of the feed pipe 9 onto the face of the distributor is uniformly distributed by the grooves therein and discharged onto the burner plate 6 partly by gravity and partly by the current of air passing laterally from under the distributor head. Some of the fuel 95 flows down over the conical burner plate and is ignited at the point where it mixes with the swirling current of air which is passing upwardly through the base of the burner and laterally from under the cover 4. The burner 100 plate becomes heated and ignition also takes place at the point where the minor current of air from under the distributor mixes with the fuel as it is delivered. Thus, combustion occurs over practically the entire surface of the 105 burner plate 6, producing a substantially solid conical flame whose outer surface has a swirling motion. The rush of air from under the distributor head causes a suction in the chamber 15 which assists the flow of oil from 110 the distributor and at the same time prevents the preignition of fuel as it flows out of the feed pipe onto the distributor head since there is no combustible mixture of air with the liquid fuel in this chamber.

115

120 To prevent carbonization of the liquid fuel flowing from the feed pipe the cover member 4 must be kept relatively cool so that the air passing under the distributor will not be unduly heated. If the interior of the burner is highly heated inefficient operation will result with carbonization and possible preignition of the liquid fuel as above pointed out. To keep the cover 4 relatively cool the burner plate is so formed that the major portion of 125 130

its surface is spaced above the cover. This annular space prevents the direct transmission of heat from the plate 6 upon which the liquid is burning to the cover 4 with a consequent high heating of the cover. With the cover kept at a lower temperature than the burner plate 6 the air passing through the burner to be mixed with the fuel in supporting combustion will not be highly heated prior to its emergence into the combustion zone, nor will the liquid fuel be heated to a point which would render the operation of the burner inefficient.

From the foregoing it will be apparent that I have provided a simple, easily assembled and efficient liquid fuel burner which can be readily installed in the usual furnace structures and which, in operation, produces a substantially solid, conical flame of great heat.

What I claim as my invention is:—

1. A liquid fuel burner having a base formed to provide a trough for the collection of excess fuel, an overflow pipe in communication with said trough, upstanding walls formed on said base and surrounding the end of said overflow pipe, a removable guard overlying said overflow pipe, said guard being provided with openings through which accumulated fuel may flow to said overflow pipe, the upstanding walls and removable guard forming a liquid seal for the overflow pipe.

2. A liquid fuel burner comprising a base provided with an interior passage for air, a cover overlying said base and spaced therefrom so that air from said passage is directed laterally between the top of the base and the cover, a burner plate supported on said cover in spaced relation therewith, the said cover

and the said burner plate provided with passages registering with the air passage of said base, a distributer for a liquid fuel supported above said burner plate in spaced relation whereby a part of the air from the passage of the base and from the passages of the cover and burner plate may flow over the burner plate under said distributer and means for supplying liquid fuel to said distributer.

3. A liquid fuel burner comprising a base defining an interior air passage, a cover for said base supported thereon in spaced relation whereby air from the base is directed laterally between the cover and the base, means between the cover and the base for imparting to the air a swirling motion, a passage through the said cover registering with the passage defined by said base, a distributer supported over the cover in spaced relation therewith whereby draft of air from the base and the cover may flow over the cover, a shield for said distributer, and means for supplying fluid fuel to said distributer.

4. A liquid fuel burner comprising a base defining an interior passage for air, a cover for said base having a passage for air registering with the passage of the base, a series of radially directed curved vanes interposed between the base and the cover and spacing them, a burner plate overlying the cover and provided with a passage registering with the passages of the base and the cover, means spaced from the burner plate for feeding liquid fuel to the upper surface thereof at a point where the air flows through the passage of said plate and means for supplying liquid fuel to the said fuel feeding means.

In testimony whereof, I have hereunto affixed my signature.

CHARLES B. BUERGER.
